US0D1008648S

(12) United States Design Patent (10) Patent No.: US D1,008,648 S
(45) Date of Patent: * Dec. 26, 2023

(54) PILL BOX

(71) Applicant: Ruiming Cen, Foshan (CN)

(72) Inventor: Ruiming Cen, Foshan (CN)

() Term: 15 Years

(21) Appl. No.: 29/843,700

(22) Filed: Jun. 23, 2022

(30) Foreign Application Priority Data

Jun. 7, 2022 (CN) 202230345075.9

(51) LOC (14) Cl. 03-01

(52) U.S. Cl.

USPC D3/203.3
